STEAM GENERATOR

Nils G. Qvarfordt, Wadsworth, Ohio, assignor to
The Babcock & Wilcox Company, Rockleigh,
N. J., a corporation of New Jersey

Application December 22, 1942, Serial No. 469,809

7 Claims. (Cl. 122—478)

This invention relates to the construction of the setting walls of a fluid heater which are exposed to high temperature conditions in operation, and more particularly, to such portions of a setting wall through which fluid heating tubes pass for connection to external headers and the like.

The main object of my invention is the provision of an improved fluid heater setting wall construction which is capable of withstanding exposure to high temperature heating gases for prolonged periods of operation without buckling or distortion while permitting relative expansion and contraction of adjacent wall portions. A more specific object is the provision of an improved wall construction for the portion of a steam boiler setting opposite a group of fluid heating tubes of relatively low heat absorption capacity, such as steam superheater tubes.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation of a three-drum separately fired superheater single uptake steam boiler incorporating my invention;

Fig. 2 is a vertical section taken on the line 2—2 of Fig. 3;

Fig. 3 is a partial horizontal section taken on the line 3—3 of Fig. 2;

Fig. 4 is a broken enlarged view of a portion of Fig. 3; and

Fig. 5 is a vertical section taken on the line 5—5 of Fig. 4.

In the drawings, I have illustrated my invention as embodied in a three-drum separately fired superheater single uptake steam boiler of the type disclosed in a copending application of E. J. Rooney, Serial No. 228,734, filed Sept. 7, 1938.

The steam generating unit illustrated comprises a setting 10 of substantially rectangular transversely elongated cross-section, a horizontally arranged steam and water drum 11 extending longitudinally thereof, a laterally offset lower water drum 12 arranged along one side thereof and connected to the drum 11 by a relatively wide inclined bank of bent steam generating tubes 13. The tube bank 13 extends the full depth of the setting, the front and rear walls 14 of which are mainly formed by refractory. At the outer side of the tube bank 13 is a vertical side wall 16 which unites with the walls 14 and roof 17 to form a gas outlet flue 18 at the outer side of the tube

bank. A bank of economizer or air heater tubes 19 can be advantageously located in the outlet flue 18.

At the inner side of and below the tube bank 5 13 is a main furnace chamber 20 fired by a plurality of fluid fuel burners 21 in the front wall 14. The remaining portion of the setting is utilized 10 for the location of steam superheating surface and an independently fired auxiliary furnace chamber for regulably heating the superheating surface. As shown, a small diameter water drum or header 25 is arranged at the opposite side of the main furnace chamber and directly below the steam and water drum 11, being connected to the 15 drum 11 by transversely spaced groups of vertically extending water tubes 26, 27, and 28. The tube rows 26 are arranged adjacent the main combustion chamber. The lower portions of these tubes are provided with projecting studs and refractory to form a closed tube baffle or partition 26^a extending from the drum 25 to the upper level of the burners 21. The tubes 27 are of larger diameter than the tubes 26 or 28 and arranged in pairs. The tubes 27 act as columns supporting the steam and water drum 11 and also serve as 20 supports for horizontally arranged superheater tubes 29 and 30 positioned between the tube groups 28 and 26.

The superheater tubes 29 are of the multi-looped type and arranged with their tube legs in vertical alignment and extending through supporting plates 31 carried by the water tubes 27 therebetween. The tubes 29 have their looped 25 portions adjacent the side walls 14 and their end tube legs connected to a pair of external vertically arranged headers 32 and 33 adjacent the same side wall 14. The superheater tubes 30 are of U-shaped form and arranged in nested rows supported by tubes 27 between the legs thereof 30 as described and with their ends connected to the header 33 and a similarly arranged header 34 adjacent thereto. The header 32 serves as the steam inlet header, the header 33 as the intermediate header, and the header 34 as the steam 35 outlet header. The superheater tubes 29 and 30 do not extend the full distance between the drums 11 and 25. The space between the upper end of the superheater and the drum 11 is closed by a baffle 36 formed on the tubes 28, while the space between the lower end and the drum 25 is closed by a similar baffle 37.

The rows of tubes 28 are arranged in staggered relation at the opposite side of the superheater from the main furnace and serve as a water tube 45 screen between the superheater tubes and an auxiliary furnace chamber 40 occupying the remaining portion of the setting. The chamber 40 extends the full width of the setting with its remaining sides defined by the tube rows 28, refractory bottom 23, a vertical outer side wall 24,

and an inclined portion of the roof 17. The side wall 24 and inclined roof portion have a row of water tubes 41 extending along the same from a bottom header 42 to the steam and water drum 11. The tubes in the forward half of the side wall, roof and baffle 26^a are of fully studded refractory covered construction, while the tubes in the remaining portion of the side wall, roof and baffle are of partly studded construction, thus providing a refractory-faced construction in the forward portion of the auxiliary furnace and alternately cold surface and refractory in the rear portion. The auxiliary furnace chamber is fired by fluid fuel burners 43 in the front wall 14. The setting also includes an outer casing 50 spaced from the refractory walls and roof to provide a space 51 through which combustion air is supplied under pressure to the fuel burner ports in the front wall 14. The casing 50 also serves to enclose water supply or downcomer connections from the drum 11 to the several generating sections of the unit.

With the described construction the steam generating unit is started up with only main furnace chamber burners 21 in use. The heating gases generated by the fuel burning in suspension therein flow transversely of the tube bank 13 and the gas outlet flue 18 passing over the heat exchanger 19 before leaving the unit. The fluid-cooled partition 26^a and tubes 26 form an effective radiant heat shield between the main furnace chamber and the superheater tubes 29 and 30. When sufficient steam is flowing through superheater tubes 29 and 30 the auxiliary furnace chamber burners 43 are started up and regulably operated to control the superheat temperature. The heating gases generated in the auxiliary furnace chamber flow substantially horizontally across the rows of screen tubes 28 and superheater tubes 29 and 30 throughout their length. After leaving the superheater tubes these gases flow across the tubes 26 and over the upper end of the partition 26^a through the extreme upper portion of the main furnace chamber 20. The gases then pass across the upper end of the tube bank 13 to the gas outlet flue 18.

The superheater headers 32, 33 and 34 are externally arranged to protect the same from direct furnace heat and contact with the high temperature heating gases from the auxiliary furnace chamber 40. Ordinarily such headers are separated from the heating gas flow path by a metal protection plate perforated for the passage therethrough of the superheater tubes for connection to the headers. Even when the protection plate is of a high heat resistant alloy, the plate portions not immediately adjacent to a superheater tube so as to benefit from its cooling effect will tend to disintegrate. Where the superheater tubes are of the multi-looped type, thereby exposing considerable plate surface between adjacent headers through which no superheater tubes project, the disintegration of the protection plate is rapid and severe.

In accordance with my invention, the portion of the setting wall 14 at the header end of the superheater tubes 29 is constructed to withstand the severe temperature conditions present, without requiring any change in position of the headers 32 or 33 or substantial increase in thickness or weight of this wall portion. As shown in Fig. 3, the side walls 14 are formed of dense firebrick 14^a backed up with insulating brick 14^b, except in the wall area opposite the header end of the superheater tubes 29 and 30. The wall portion at

the header end of the tubes 30 is formed by a protection plate 55 of heat resistant alloy through which the ends of the tubes project. The portion of the plate 55 between the tube legs is backed with a channel 56 enclosing heat insulating material 57. The end of the plate 55 adjacent the header 33 extends beyond the tubes 29 connected to that header and terminates in a vertical outwardly extending flange 58. In view of the substantial cooling effect of the tubes 30 in contact with the plate 55, the described construction is adequate for the temperature conditions to which it is normally exposed.

The portion of the inner wall 14 opposite the looped portions at the header end of the tubes 29 is given a special construction to enable it to withstand the higher temperature conditions to which it is normally exposed in operation, yet without requiring any change in location or construction of the associated headers 32 and 33. This wall section is formed by a row of spaced vertical water tubes 60 having their upper and lower ends bent rearwardly and connected to the upper and lower drums 11 and 25 respectively. The tubes 60 are of the partially studded type, having metallic studs 61 projecting from opposite sides thereof into the intertube spaces. Each tube also has one or two vertical rows of vertically elongated metallic plates 62 preferably welded to the tubes and studs at the inner side of the wall and extending along the inner studs to a point substantially in contact with the plates from the adjacent water tubes 60. The plates 62 form a retaining wall for a suitable high temperature resistant filler material 63, such as plastic chrome ore, positioned in the intertube spaces. The tubes 60, studs 61, retainer plates 62, and filler material 63 thus cooperate to form a water cooled panel wall section of high heat absorbing capacity adjacent the looped portions of the superheater tubes 29 for the full length of the superheater headers 32 and 33.

The provision of a water cooled panel wall section in this location creates a differential expansion condition between the water cooled wall section and the adjacent superheater headers and tube ends. To permit such relative vertical expansion and contraction flanged plates 65 are welded to the outer row of studs adjacent the protection plate flange 58 and the flanges bolted together through vertically elongated slots as indicated at 66 to permit relative vertical movement of the flanges.

At the opposite side of the water cooled wall section a metallic plate 67 is secured to the adjacent wall portion and header 32 and carries a finger plate 68 which fits around the first water tube 60 with its flanged end in sliding contact with finger plates 69 mounted on the rear portion of the first tube 60. The plates 67 and 68 are further protected by a brick ledge 70 which projects inwardly from the wall 14 and a stud tube baffle 71 extending between the two adjacent tubes 28 for the full height of the superheater. The heating gas flow is thus deflected sufficiently to minimize direct impingement of the gases on these plates. The spaces between the headers 32, 33 and 34 and between the headers 32 and 34 and the adjoining refractory portions of the wall 14 are sealed by packing 73 and suitable sliding seals 74 to separate the space occupied by the panel wall section from the air space 51.

The described wall construction for the superheater section of the unit provides an effective

closure for this section without necessitating relocation or modification of the superheater headers or any substantial increase in weight of the wall. The amount of steam generating surface is increased without increasing the space requirements of the unit. Differential thermal expansion and contraction of the associated parts is facilitated with the described wall construction.

While in accordance with the provisions of the statutes I have illustrated and described herein the best form of the invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. In a fluid heater having a setting wall, a pair of horizontally spaced vertical headers positioned at the outer side of said wall, and a bank of horizontally arranged multi-looped tubes having horizontally spaced tube legs projecting through said wall for connection to said headers, the improvement which comprises a wall section between said projecting tube legs having a row of spaced vertical tubes, means closing the intertube spaces in said row including metallic studs on said vertical tubes projecting into said intertube spaces, refractory material surrounding said studs, and retainer plates secured to the inner sides of said tubes and arranged to hold said refractory material in position, and relatively movable connecting means forming a slidable joint between said wall section and the adjacent setting wall portions.

2. In a steam generator having a setting wall, an upper steam and water drum, a lower water drum, spaced groups of vertical water tubes connecting said drums, a pair of vertical steam superheater headers positioned at the outer side of said wall, a bank of horizontally arranged multi-looped superheater tubes between said water tube groups and having horizontally spaced tube legs adapted to project through said wall for connection to said headers, a wall section between said projecting tube legs having a row of spaced vertical water tubes having their ends connected to said upper and lower drums, means closing the intertube spaces in said tube row including metallic studs on said vertical water tubes projecting into said intertube spaces, refractory material surrounding said studs, and retainer plates mounted on said vertical water tubes and arranged to hold said refractory material in position, and relatively movable connecting means forming a slidable joint between said wall section and the adjacent setting wall portions.

3. In a fluid heater having a setting wall, a pair of headers positioned at the outer side of said wall, and a bank of tubes having spaced tube legs projecting through said wall for connection to said headers, the improvement which comprises a panel wall section between said projecting tube legs having a row of spaced wall cooling tubes extending substantially parallel to said headers, means closing the intertube spaces in said row, and relatively movable connecting means forming a slidable joint between said panel wall section and the adjacent setting wall portions constructed and arranged to provide for relative thermal expansion and contraction between said panel wall section and said tube legs and headers.

4. In a fluid heater having a setting wall, a

pair of headers positioned at the outer side of said wall, and a bank of horizontally arranged multi-looped tubes having horizontally spaced tube legs projecting through said wall for connection to said headers, the improvement which comprises a wall section between said projecting tube legs having a row of spaced vertical wall cooling tubes, means closing the intertube spaces in said row, and relatively movable connecting means forming a slidable joint between said wall section and the adjacent setting wall portions connected and arranged to provide for relative vertical thermal expansion and contraction between said wall section and said tube legs and headers.

5. In a steam generator having a setting wall, a pair of horizontally spaced vertical steam superheater headers positioned at the outer side of said wall, and a bank of multi-looped superheater tubes having horizontally spaced tube legs projecting through said wall for connection to said headers, the improvement which comprises a wall section between said projecting tube legs having a row of spaced vertical water tubes, means closing the intertube spaces in said row, and relatively movable connecting means forming a slidable joint between said wall section and the adjacent setting wall portions constructed and arranged to provide for relative vertical thermal expansion and contraction between said wall section and said tube legs and headers.

6. In a steam generator having a setting wall, an upper steam and water drum, a lower water drum, spaced groups of vertical water tubes connecting said drums, a pair of vertical steam superheater headers positioned at the outer side of said wall, a bank of multi-looped superheater tubes between said water tube groups and having horizontally spaced tube legs adapted to project through said wall for connection to said headers, a wall section between said projecting tube legs having a row of spaced vertical water tubes having their ends connected to said upper and lower drums, means closing the intertube spaces in said tube row, and relatively movable connecting means forming a slidable joint between said wall section and the adjacent setting wall portions constructed and arranged to provide relative vertical thermal expansion and contraction between said wall section and said superheater tube legs and headers.

7. In a steam generator having a setting wall, an upper steam and water drum, a lower water drum, spaced groups of vertical water tubes connecting said drums, a pair of vertical steam superheater headers positioned at the outer side of said wall, a bank of horizontally arranged multi-looped superheater tubes between said water tube groups and having horizontally spaced tube legs adapted to project through said wall for connection to said headers, a wall section between said projecting tube legs having a row of spaced vertical water tubes having their ends connected to said upper and lower drums, means closing the intertube spaces in said tube row, relatively movable connecting means forming a slidable joint between said wall section and the adjacent setting wall portions constructed and arranged to provide for relative vertical thermal expansion and contraction between said wall section and said superheater tube legs and headers, and a vertical ledge on the inner side of said setting wall arranged to deflect heating gases away from said wall section.

NILS G. QVARFORDT.
